CLAIM

The ornamental design for a protective cage for bicycle meters, timers, and cycle computers, as shown and described.

DESCRIPTION

FIG. 1 is a bottom plan view of a protective cage for bicycle meters, timers, and cycle computers showing my new design;

FIG. 2 is a front elevational view thereof;

FIG. 3 is a left side elevational view, the right side elevational view being the mirror image thereof;

FIG. 4 is a rear elevational view thereof; and,

FIG. 5 is a top plan view thereof.

FIG. 1

FIG. 3

FIG. 2

FIG. 5

FIG. 4
